UNITED STATES PATENT OFFICE.

ELMER E. GALLAHER, OF GAS CITY, AND DOMINICK J. MCGRAIL, OF MARION, INDIANA.

AUTOMATIC MOLD-CHARGING MECHANISM.

1,229,060.

Specification of Letters Patent.

Patented June 5, 1917.

Application filed July 28, 1915. Serial No. 42,375.

To all whom it may concern:

Be it known that we, ELMER E. GALLAHER and DOMINICK J. MCGRAIL, citizens of the United States, residing at Gas City, in the county of Grant and State of Indiana, and Marion, in the county of Grant and State of Indiana, respectively, have invented certain new and useful Improvements in Automatic Mold-Charging Mechanism, of which 10 the following is a specification.

The present invention relates to improvements in automatic mold charging mechanisms, especially as adapted to the art of glass manufacture, its object being to provide suitable means to replace the conventional hand process of dipping or gathering the molten material, and by which means the said material is measured accurately and automatically transferred to the molds. 15 The essence of the invention lies in the provision of mechanism disposed intermediate the furnace or tank in which the molten glass is contained and the molds to receive the same, said mechanism comprising a support carrying a receiving cup or measuring receptacle into which the glass is admitted, said receptacle being mounted upon a weighing beam which latter is utilized to automatically actuate operating means, upon receipt of a predetermined amount of material in the cup, for shearing the stream and simultaneously discharging the material into the mold positioned to receive it, and finally starting the pressing machinery which may be employed in carrying out the 20 complete process of the manufacture.

A further object in view is to provide a special construction of measuring receptacle, divided in form and the sections of which are operated to cause opening and closing thereof through operative connections with the shearing mechanism.

A still further object we have in mind is to provide means for controlling the accuracy of the weighing operation, said means constituting, in performing its function, cooling means for the measuring receptacle, as well as acting as a substantial air cushion therefor.

As will be apparent to those skilled in the art to which the device refers, many advantages accrue to the use of our invention, among which may be mentioned a substantial improvement in the articles of manufacture themselves and the elimination of loss

due to imperfect ware usually caused by placing too large or too small a quantity of the material in the molds or the exposure of the same to the air for too long a period of time; the saving of labor and the increase 60 in the output possible are also advantageous features of its use.

These and such other objects as may hereinafter appear are attained by the novel construction, combination, and arrangement 65 of parts to be hereinafter specifically described and claimed. Reference will now be had to the accompanying drawings forming a part of this specification, wherein:

Figure 1 is a side elevation of an apparatus forming the embodiment of our invention. 70

Fig. 2 is a top plan view thereof, parts being broken away and shown in section to disclose more clearly the details of construction. 75

Fig. 3 is a bottom plan view.

Fig. 4 is a vertical sectional view on the line indicated 4-4 in Fig. 1.

Fig. 5 is a similar section on the line 5-5 80 of Fig. 1.

Fig. 6 is a similar section on the line 6-6 of Fig. 1.

Fig. 7 is a perspective view of the controlling means employed with our device 85 for regulating the accuracy of the weighing mechanism.

Fig. 8 is a perspective view illustrating the combined molding and pressing instrumentalities. 90

Throughout the following detail description, and on the several figures of the drawings, similar parts are referred to by like reference characters.

In describing the device it may be here premised that while we use compressed air as a medium for operating the shearing mechanism and accomplishing the discharge action of the measuring instrumentalities, we do not wish to be limited to such use, 100 as it is within the purview of our invention to utilize any desired actuating means for performing these functions which will serve with equal facility and it will also be understood that the machine may coöperate with any known type of melting and molding apparatus including pressing mechanism, which latter, not forming the subject of our invention, will only be referred to generally.

A designates a frame or plate of any de- 105

sired form or configuration, but preferably of metal construction, horizontally disposed for support by a post B to which it is adjustably connected by a clamping member 5 C movable vertically up or down on the post so as to enable adjustment of the device in proper relation to the mold or molds which are disposed beneath the same. As most clearly shown in Fig. 6, the clamp C is 10 grooved longitudinally to receive the support A which is held in its adjusted position as by means of the bolts or other fastening devices D.

Depending from beneath the frame A are 15 a pair of spaced brackets or supports 1 secured thereto by the fastening members 2. In suitable openings in said brackets is pivotally mounted a beam 3, the trunnions 3' for which rest upon set screws 4. The beam 20 3 is formed at one end with graduations as indicated at 5 and carries an adjustable weight or pea 6 and which may be fixed at any predetermined point of adjustment by its set screw 7. The opposite end of the 25 beam carries a measuring receptacle or cup 8, divided longitudinally, one section of which is fixed to the disk 9 loosely mounted on the end of the beam 3 and the other section likewise secured to the annular collar 10 rotatably mounted on and surrounding this disk. The cup is located directly beneath a circular opening 11, in the end 30 of the support A, through which the molten glass or other plastic material, as the case 35 may be, passes from the furnace or tank, the outlet or trough of the same being indicated in dotted lines in Fig. 1, at 12. Within said opening 11 is seated a thimble 13, of non-heat conducting material, and 40 designed to prevent the heat from affecting the support A.

In conjunction with this apparatus, we 45 employ shearing mechanism for severing the stream of glass automatically when a predetermined quantity of the same has dropped or flowed into the cup 8, as controlled primarily by the weight on the beam 3. To this end the support A is suitably formed at the extremity over the cup to receive coacting shearing elements 14, 14', 50 slidably mounted for movement transversely of the support for shearing action, the inner ends of said elements being correspondingly notched as indicated at 15. These shears are 55 actuated simultaneously as the cup elements or sections are opened in a manner and by means now to be described.

Just above the beam 3 at its weighted side 60 in the support or frame A is located an air valve 16, including a trip member or valve stem 17 projecting downwardly therefrom for coöperation with said beam. To this valve is led, as by means of a conduit or pipe 18 passing downwardly through the 65 support A, as shown in Fig. 2, and laterally

into the valve as shown in Fig. 3, air under pressure. Of course, it will be understood that instead of air any fluid pressure such as steam may readily be employed for this purpose and performing the same functions 70 as here described. The valve 16 is placed in communication with a pressure cylinder 19 on top of the support A by the tube 20; the piston for this cylinder being connected through its rod 21 to a pair of toggle links 22, in turn connected with a pair of corresponding spaced levers 23, 24, pivoted at 23' and 24' respectively. The lever 23 is bifurcated at its free extremity where it engages a vertical projection or post 25 carried by a longitudinally extending bar 26 which is secured 80 at right angles to the shear element 14'. As most clearly shown in Fig. 5, a notched bar, substantially a rack bar 27 projects laterally from the bar 26 and the end of said bar 27 engages between spaced teeth 28 of a disk 29. The latter is carried by the end of the beam 3 and is fixed in relation to the disk 9 to which one of the cup sections is secured. In like manner the lever 24 is 85 connected with the post 30 on the bar 31, connected to the shear element 14, and a corresponding projecting notched bar 32 engages between the projections 33 extending rearwardly from the collar 10 to which the other 90 cup section is connected. When the piston in the cylinder 19 reaches the end of its stroke, the air is exhausted through the conduit 34 from which it may be utilized for any further purpose desired but in this case 100 for starting the pressing mechanism as will be later set forth.

The end of the support A in which the shears are mounted is constructed so as to permit of keeping the shears cooled. Air 105 conduits (not shown) lead to the openings 35, one of each of which is located just above each shear member (see Fig. 2). The cooling medium is also led through the pipe 36 to the passage 37 leading to an annular 110 groove or recess 38 in the edge of the opening 11. This is designed with a view to keeping the thimble 13 cooled, the air circulating therearound and exhausting out of the passage 37.

The operation of the apparatus as thus far described will be apparent from the drawings and the foregoing description. When the mold has been brought to a proper position beneath the cup 8, and assuming that the support A has been adjusted both vertically and horizontally, the molten material is allowed to flow from the tank or furnace through the thimble 13 and into the divided cup 8. As soon as a sufficient quantity is received thereinto, as determined by the weight 6 on the beam 3, said beam will be tilted, raising up the trip member or stem 17 and opening the valve 16, thereby admitting air under pressure 125 130 135 140 145 150

into the cylinder 19, whereupon its piston actuates the levers 23 and 24 which in turn impart shifting movement to the shears and simultaneously open the cup sections through 5 the bars 27 and 32, and the members 29 and 33. The molten mass, at this time, falls into the mold and the pressing mechanism is thereupon started under the control of the air passing through the conduit 34 as 10 hereinbefore mentioned. The air having exhausted the cup members and shears assume their normal position and the beam also falls to its initial position due to the weighted parts of each element, the action 15 of the apparatus from the outstart being entirely automatic. Movement of the beam 3 is limited when the cup is emptied by the strap or yoke 39.

To a certain extent the perfection of 20 manufacture of articles by the flowing glass method depends upon the constituency of the material admitted to the molds and to best carry out this process we find it advantageous to employ auxiliary means 25 for regulating the weight of the glass dropping between the shears and the cup so as to obtain accuracy of the weight regardless of whether the glass is cool or hot. Obviously if the molten material is hot it 30 flows in a small stream but if cool, relatively speaking, in a larger stream. Therefore, if the glass is sheared at a given point above the receptacle into which it is being poured, there would be more weight in one 35 instance than in the other which would drop after the stream had been cut. Hence, to provide an adequate control for the condition, we provide an air cushion so to speak beneath the cup 8 as most clearly 40 shown in Fig. 7. This consists of a pipe 40 sustained by a bracket 41 carried by the frame or support A and, therefore, adjustable with it, the pipe being adjustably clamped to the lower end of the bracket 45 and provided with spaced branches 41', 41' disposed at opposite sides of the cup, such branches having a plurality of openings to allow the air under pressure to escape and blow against said cup at substantially 50 an angle of forty-five degrees. This air is supplied through the conduit 42 and a valve 43 controls the flow or pressure. As will be apparent the higher the pressure, the greater the amount of material 55 will be necessary to accomplish the tripping and discharge of the glass as the air pressure tends to counteract the weight on the beam. The operator may readily attain skill in keeping the weight exact 60 by regulating the valve from time to time according to the character or fluidity of the molten glass. The process leads to the elimination of short weight of articles manufactured, and what is more desirable, to the 65 prevention of "flanging" of the articles

due to overflow of the molds. In addition, the action of the air on the cup tends to keep it cooled which is quite desirable at this stage of the operation.

As hereinbefore mentioned, the exhausting pressure from the cylinder 19 is further utilized to start operation of the pressing mechanism, the coaction being disclosed by Fig. 8. The air passes by way of the conduit 34 through the support B to the cylinders 44, the pistons 45 of which revolve the mold table 46, bringing the next receiving mold into position beneath the pressing member 47 which then operates in the usual way to form the material.

Having thus described our invention, what we claim as new is:

1. Mold charging mechanism of the class described comprising, in combination, a weighing beam, a receiving cup extending from one end of the beam and having its longitudinal axis coincident with the longitudinal axis of said beam, counterbalance means on the other end of the beam, and movable means intermediate the cup and the counterbalance means adapted for actuation by the beam, whereby to discharge the cup.

2. Mold charging mechanism of the class described comprising, in combination, a weighing beam, a receiving cup rotatably mounted on an end portion of the beam, counterbalance means on the other end portion of the beam, and means for rotating the cup when said cup has received a predetermined amount of material, to discharge the cup simultaneously with the balancing thereof.

3. Mold charging mechanism of the class described comprising in combination, a weighing beam, counterbalance means thereon, a receiving cup comprising openable sections journaled on an end portion of the beam, and actuating means operatively connected to the journaled portions of the cup sections, for opening the same under control of the counterbalance means upon receipt of a predetermined amount of material in said cup.

4. Mold charging mechanism of the class described comprising, in combination, a weighing beam, a sectional glass receiving cup controlling movement of said beam upon reception of a predetermined amount of the glass material, shearing members for severing the stream of glass falling into the cup, separate means coaxially mounted on said beam for rotating the cup sections a partial revolution to open the same, actuating levers for said shearing members, an operative connection intermediate a lever and each of the rotating means for the cup sections, and means controlled by the beam for operating the shearing mechanism and said cup sections.

- 41
5. Charging mechanism for glass molds comprising in combination, a pivotal supporting member, a receptacle on said supporting member at one side of the pivot, 5 balance means on the supporting member at the other side of the pivot, and means on the same side of the pivot as the receptacle tending to resist the downward movement of said receptacle.
- 10 6. Charging mechanism for glass molds comprising in combination, a glass receiving receptacle, weighing mechanism for controlling discharge of said receptacle, and means to supply a pressure medium to act against 15 the receptacle to more or less resist downward movement of the receptacle.
7. Charging mechanism for glass molds comprising in combination a glass receiving receptacle, weighing mechanism for controlling discharge of said receptacle, pressure 20 supply means arranged to act against the receptacle to more or less resist downward movement of the receptacle, and means for regulating the pressure supply means where- 25 by to maintain accuracy of the weighing mechanism according to the constituency of the glass material.
8. Charging mechanism for glass molds comprising in combination a glass receiving 30 receptacle, shearing mechanism for severing the stream of glass at a predetermined point above the receptacle, weighing mechanism at one side of the receptacle for controlling discharge of the receptacle and operation of 35 the shearing mechanism, and auxiliary pressure controlling means operable on the receptacle to resist premature discharge there- 40 of due to change of constituency of the glass stream intermediate the shearing mechanism and the receptacle.
9. Charging mechanism for glass molds comprising in combination a glass receiving receptacle, weighing mechanism for controlling discharging of said receptacle, and 45 means for regulating the latter according to the constituency of the glass material, said means constituting cooling means for the receptacle.
10. Charging mechanism for glass molds comprising in combination a glass receiving 50 receptacle, weighing mechanism for controlling discharge of said receptacle, and means providing an air cushion for the receptacle.
11. The combination with glass molds, of 55 charging mechanism therefor comprising a support having an opening therethrough through which molten material is adapted to pass, a receptacle suspended from said support beneath the opening to receive the 60 molten material preliminary to charging the molds aforesaid from said receptacle, a removable protective shell surrounding the opening of the support, shearing members carried by the support below the protective member, means for maintaining the protec- 65 tive member and shearing members cooled, and means for discharging the receptacle into the molds.
12. In apparatus of the class described for charging glass molds, the combination 70 of a glass receiving receptacle, pressing mechanism for forming the material when discharged into the molds, and weighing means for controlling the discharge of the receptacle and subsequent operation of the 75 pressing mechanism.
13. In apparatus of the class described for charging molds, the combination of a glass receiving receptacle, shearing mechanism including operating means, pressing 80 mechanism for forming the material when discharged into the molds, and means con- 85 trolled by the receptacle for simultaneously actuating the shearing mechanism and discharging the receptacle, and subsequently actuating the pressing mechanism under the control of the operating means aforesaid.
14. In apparatus of the class described for charging molds, the combination of a glass receiving receptacle, shearing mecha- 90 nism, pressing mechanism for forming the material when discharged into the molds, pressure control means for actuating the shearing mechanism and discharging the re- 95 ceptacle, and means operable by the recep- 100 tacle upon reception of a predetermined amount of material for releasing the pressure means, said last mentioned means also subsequently starting the pressing mecha- 105 nism under the control of the shearing mechanism.
15. In apparatus of the class described for charging molds, the combination of a glass receiving receptacle, shearing mecha- 110 nism, pressing mechanism for forming the material when discharged into the molds, a pressure cylinder for actuating the shearing mechanism and discharging the receptacle, and a valve for said cylinder operable upon 115 reception of a predetermined amount of ma- 120 terial in said receptacle for operating the shearing mechanism and discharging the re- 125 ceptacle, said cylinder controlling starting of the pressing mechanism.
16. In apparatus of the class described for charging molds, the combination of a glass receiving receptacle, a weighing beam to which said receptacle is connected, shearing mechanism, pressing mechanism for 130 forming the material when discharged into the molds, a pressure cylinder including a piston operably connected to the shearing mechanism and the receptacle for actuating the former and discharging said receptacle, and a valve controlling admission of pres- 135 sure to said cylinder and operable by the beam aforesaid upon receipt of a predetermined amount of material in said receptacle, said cylinder having an exhaust for establishing communication between the 140

cylinder and the pressing mechanism whereby to start the latter upon discharge of the contents of the receptacle into the molds.

5 17. In combination, weighing, shearing, table actuating and pressing mechanisms, a series of pressure operated devices coacting with the respective mechanisms, a continuous pressure line in which said operated 10 devices are interposed, each device in

turn constituting communication-establishing means for admitting the pressure to the next succeeding pressure device whereby the mechanisms aforesaid are progressively operated through continuity of the pressure. 15

In testimony whereof we affix our signatures.

ELMER E. GALLAHER.
